UNITED STATES PATENT OFFICE.

HARRY W. BROADY, OF BAYSIDE, NEW YORK, ASSIGNOR TO WELIN MARINE EQUIPMENT COMPANY, A CORPORATION OF NEW YORK.

LIFE-LINE PROJECTILE.

1,142,396.

Specification of Letters Patent. Patented June 8, 1915.

Application filed September 26, 1913. Serial No. 791,893.

To all whom it may concern:

Be it known that I, HARRY W. BROADY, a citizen of the United States, and a resident of Bayside, borough of Queens, county of 5 Queens, and State of New York, have invented certain new and useful Improvements in Life-Line Projectiles, of which the following is a specification.

This invention relates to improvements in 10 life-line projectiles.

By the use of my invention a lifeline projectile is so designed that it will first, receive the full projecting force of the charge within the gun; second, have an efficient, 15 bearing surface along the sides of the gun; third, pursue a direct course after it leaves the gun without presenting a broadside to the air; fourth, substantially all progress impeding projections beyond the periphery 20 of the projectile are eliminated; fifth, the connection between the projectile and the lifeline will be made by means of a transversely-extending stationary pin located at a point slightly to the rear of the center of 25 gravity and in the longitudinal axis of the projectile, a longitudinally-disposed radial slot having flat sides and diverging front and rear walls extending from the said point of connection to the periphery of the projectile so as to permit the connection and 30 vertical swinging of a flexible connecting rod preferably formed of wire rope, between which rod and the lifeline proper suitable shock-absorbing means, such as a spring, 35 may if desired be interposed.

In the accompanying drawings, in which similar reference characters designate corresponding parts throughout the several views, Figure 1 is a side elevation of a gun 40 with a projectile embodying my invention seated therein before firing and showing, in broken lines, the direction of travel of the projectile and the change of position of the line-attaching means relatively thereto; Fig. 45 2 is an enlarged central longitudinal section of a gun with my improved projectile seated therein, showing the radial slot to permit the vertical swinging of the line-attaching or connecting rod, and its position before 50 firing; Fig. 3 is a side elevation of my projectile showing in dotted lines the said radial slot and the position of connecting rod after 55 firing; and Fig. 4 is a section on the line 4-4 of Fig. 3 looking in the direction of the arrow.

Referring now to the accompanying drawings, 1 indicates a projectile body which, as shown, is in the form of an elongated cylinder so as to conform to the bore of a discharging gun 2 and present an even bearing surface to such bore, has a flat vertical rear end 3 so as to receive the maximum of explosive force from the charge within the explosion chamber of the gun within which it is seated, and has its forward end acutely 60 pointed as at 4 so as to cut the air with a minimum of frictional resistance after its discharge.

I have found that the most efficient lifeline carrying position for a projectile of the 65 character herein described is at a point slightly to the rear of the center of gravity of the projectile and in its longitudinal axis, and also that any sliding movement of the line-attaching means relatively to the projectile 70 is undesirable. In order to permit the attachment of the lifeline to the projectile at said point, I preferably provide a radial slot 5 extending from the point of connection to the periphery of the projectile and having flat sides 5^a-5^a and diverging front and rear ends 5^b-5^c, the slot 5 thus forming a channel to permit the vertical swinging 75 of a flexible connecting rod 6 preferably formed of wire rope which is pivoted to the transverse center of a pin 7 extending transversely across the longitudinal axis of the projectile at a point slightly to the rear of the center of gravity, as aforesaid, and the front wall 5^b of the radial slot 5 is preferably 80 somewhat deeper at the front of the device to permit the flexible rod to project beyond the bore of the gun before firing, the rear diverging wall of said slot terminating adjacent to the solid flat rear ends of the projectile. If desired, suitable means such as 85 the spring 8 may be interposed between the line 9 of the rod to take up shock or jar therebetween, though I have found that a rod formed of wire rope, as aforesaid, will in itself take up shock and may be used without interposing any further shock-absorbing device. Furthermore such a flexible 90 rod will not only take the shape of the slot but its rear portion will conform to the direction of travel of the projectile so that the line will receive a direct pull close to the path of travel of the projectile.

Having described my invention, I claim:

1. A lifeline projectile embodying an elongated

- gated cylindrical body substantially uniform in diameter having a pointed forward end, a line attaching pin extending transversely across the longitudinal axis of the device 5 adjacent to the center of gravity of the projectile, a longitudinally-disposed radial slot formed in said body and communicating between the outer periphery thereof and said pin and a lifeline movable within said slot 10 from the front to the rear of the projectile.
2. A lifeline projectile embodying an elongated cylindrical body substantially uniform in diameter, having a pointed forward end, a line-attaching pin extending transversely 15 across the longitudinal axis of the device adjacent to and at the rear of the center of gravity of the projectile, a longitudinally-disposed radial slot formed in said cylindrical body and having flat sides and diverging 20 front and rear ends extending from the transverse center of said pin outwardly to the periphery of the projectile, and a lifeline connected to the transverse center of said pin within said slot.
3. A lifeline projectile embodying an elongated cylindrical body substantially uniform, in diameter, having a pointed forward end, a line-attaching pin extending transversely 25 across the longitudinal axis of the device adjacent to and at the rear of the center of gravity of the projectile, a longitudinally-disposed radial slot formed in said cylindrical body and having flat sides and diverging 30 front and rear ends extending from the transverse center of said pin outwardly to the periphery of the projectile and a rod pivoted to the center of said pin within said 35 slot and adapted to project outwardly beyond the bore of the discharging gun and to swing vertically in said slot from the front to the rear thereof after its discharge.
4. A lifeline projectile embodying an elongated cylindrical body substantially uniform 40 in diameter, having a pointed forward end, a line-attaching pin extending transversely across the longitudinal axis of the device adjacent to and at the rear of the center of gravity of the projectile, a longitudinally-disposed radial slot formed in said cylindrical body and having flat sides and diverging 45 front and rear ends extending from the transverse center of said pin outwardly to the periphery of the projectile and a flexible rod formed of wire rope pivoted to the center of said pin within said slot and adapted 50 to project outwardly beyond the bore of the discharging gun and to swing vertically in said slot from the front to the rear thereof after its discharge.
5. A lifeline projectile embodying an elongated cylindrical body substantially uniform in diameter, having a pointed forward end, a line-attaching pin extending transversely 55 across the longitudinal axis of the device adjacent to and at the rear of the center of gravity of the projectile, a longitudinally-disposed radial slot formed in said cylindrical body and having flat sides and diverging 60 front and rear ends extending from the transverse center of said pin outwardly to the periphery of the projectile, a rod pivoted to the center of said pin within said slot and adapted to project outwardly beyond the bore of the discharging gun and to swing vertically in said slot from the front to the rear thereof after its discharge.
- In witness whereof, I have signed my name to the foregoing specification in the presence of two subscribing witnesses.

HARRY W. BROADY.
